UNITED STATES PATENT OFFICE.

ABIRAM J. SLONECKER, OF TRENTON, MISSOURI.

BELT-LACING.

950,009.

Specification of Letters Patent. Patented Feb. 22, 1910.

Application filed April 12, 1909. Serial No. 489,405.

To all whom it may concern:

Be it known that I, ABIRAM J. SLONECKER, a citizen of the United States, residing at Trenton, in the county of Grundy and State 5 of Missouri, have invented a new and useful Belt-Lacing, of which the following is a specification.

This invention relates to belt lacing and its object is to provide means whereby the 10 connected ends of a belt can be separated without the necessity of disturbing the thongs used for lacing purposes.

Another object is to provide lacing which can be very quickly adjusted and which 15 does not require the use of long thongs as heretofore.

Another object is to provide a lacing having the strains distributed equally throughout the lengths thereof, said lacing forming 20 a flexible hinge without increasing the thickness of the belt at the point of connection.

A still further object is to provide lacing which permits the belt to be properly adjusted prior to being placed on a line of 25 shafting.

With these and other objects in view the invention consists of certain novel details of construction and combinations of parts 30 hereinafter more fully described and pointed out in the claims.

In the accompanying drawings the preferred form of the invention has been shown.

In said drawings:—Figure 1 is a perspective view of the lacing, the thongs being 35 shown in the positions assumed by them when the parts are secured together, the belt and the key being shown by dotted lines. Fig. 2 is a plan view of the end portions of the belt, the thongs, and the key, the two 40 belt ends being shown separated.

Referring to the figures by characters of reference A designates a belt having outer and inner rows of apertures 1 and 2 respectively adjacent each end thereof, there also 45 being a slit 3 adjacent one of the longitudinal edges of the belt and near the apertures.

One lacing thong is provided for each end of the belt. Each thong, which has been 50 indicated by the numeral 4, has a slit 5 cut in one end, said end being inserted through one of the end apertures 1. The thong is then looped around the end of the belt and inserted through the slit and passed thence 55 through the adjoining opening 2, after which it is extended along diagonal lines to

the next opening 1, from which it is looped around the end of the belt and brought back to the adjoining opening 2, this arrangement being followed throughout the width 60 of the belt, the end of the thong being finally passed from the end opening 2 and through the slit 3 so as to leave a free tongue 6. It will thus be seen that several loops will be provided beyond the end of the belt. 65 Both ends of the belt are provided with a thong threaded therethrough in this manner, the loops on one end of the belt however being so arranged that when the two ends are brought together said loops will project between those on the opposite end of the belt. This arrangement has been clearly indicated in Fig. 1. After the two sets of loops have thus been brought together as shown in Fig. 1 a key 7 preferably in the 70 form of a round pin is inserted through the loops, said pin being provided at its ends with openings 8 through which the tongues 6 are designed to be inserted, these tongues thus serving to prevent longitudinal 75 displacement of the key. The ends of the tongues can then be inserted between the various loops of the thongs so as to be held out of the way.

It will be understood that whenever it is 85 desired to uncouple the ends of the belt it is merely necessary to unfasten the key 7 and withdraw it from the loops formed by the thongs. It will be seen therefore that the belt can be laced upon the floor and subsequently placed upon the shafts and its ends then fastened together by inserting the key 90 through the registering loops. Attention is directed to the fact that those portions of the thongs which bear upon the pulleys extend 95 in the direction of the length of the belt and therefore they are rendered more lasting than where they are extended along diagonal lines.

By providing a lacing such as herein described it is only necessary to use short thongs which can be very quickly placed in position, the arrangement of the loops being such as to cause the equal distribution of all strains throughout the lengths of the thongs. 105

What is claimed is:—

1. A belt having a flexible member threaded through each end portion thereof to form loops extending beyond said end, the loops on the meeting ends of the belt being movable into register, an apertured key insertible into the registering portions of the 110

loops, one of said flexible members having one end insertible into the aperture in the key.

2. A belt having a flexible member threaded through each end thereof, said member forming loops extending beyond the end of the belt, the loops on one end of the belt being movable into position between the loops on the adjoining end thereof, a key insertible into the lapping portions of the loops and having apertures adjacent the

ends thereof, one terminal of each flexible member being insertible into each of the apertures.

In testimony that I claim the foregoing ¹⁵ as my own, I hereto affix my signature in the presence of two witnesses.

ABIRAM J. SLONECKER.
